UNITED STATES PATENT OFFICE.

DANIEL S. BURKHART, OF SPOKANE, WASHINGTON.

FIRE-ESCAPE.

1,164,988.

Specification of Letters Patent. Patented Dec. 21, 1915.

Application filed December 12, 1914. Serial No. 876,995.

To all whom it may concern:

Be it known that I, DANIEL S. BURKHART, a citizen of the United States, residing at Spokane, in the county of Spokane and State of Washington, have invented certain new and useful Improvements in Fire-Escapes, of which the following is a specification.

This invention relates to improvements in fire escapes and has to do more particularly with the endless type whereon treads are mounted to support the user.

It is one of the objects of my invention to provide means whereby the endless carrier will always be maintained sufficiently taut to be effectively operated, this feature of my invention being of particular importance where the endless carrier is in the form of chains trained about sprocket wheels.

It is a further object of this invention to provide a fire escape of the endless type which is adapted to be actuated by the weight of the user and to which a governing device is applied to retard descent of the user and prevent the escape from racing.

A still further object of the invention is to provide means whereby the fire escape can be used either for descent or ascent thereby enabling the device of my invention to be used as an elevator for rescuers or firemen after the occupants have escaped.

A still further object of the invention is to provide a novel form of chain and sprocket which is particularly adapted for use in an endless type of fire escape and which functions to not only afford a smoothly running device but one in which is combined the necessary strength and reduction of bulk and weight.

Other features and objects of the invention will be more fully described in connection with the accompanying drawings and will be more particularly pointed out in and by the appended claims.

In the drawings:—Figure 1 is a view in side elevation showing one embodiment of my invention. Fig. 2 is a front elevation thereof. Fig. 3 is an enlarged view in elevation of one of the lower mountings. Fig. 4 is a view in elevation, of Fig. 3, looking in the direction of arrow 4. Fig. 5 is a perspective view of one of the treads used in connection with my improved fire escape. Fig. 6 is a perspective view of a portion of the novel form of chain, used in connection with my invention. Fig. 7 is a side view of

a novel form of sprocket wheel. Fig. 8 is an edge view of the sprocket wheels shown in Fig. 7.

Like characters of reference designate 60 similar parts throughout the different figures of the drawings.

As illustrated, my improved fire escape is shown mounted upon the side wall 1 of a building, and includes upper and lower 65 shafts 2 and 3. I will term the upper shaft 2, the governed shaft and the lower shaft 3, the operating shaft.

The upper shaft 2 has one end thereof journaled in any suitable form of bearing 4 70 which may be fixed to the side of the building 1. The remaining end of shaft 2 is journaled in a governor bearing structure 5, which is fixed to the building and in which is incorporated a governor, indicated as a 75 whole at 6, and which may be of any approved type, one form being illustrated in my application filed December 12, 1914, Serial No. 876,996. For the purposes of the present disclosure, I have indicated a governor shaft 7, which is controlled by the governor, as being provided with a gear 8, meshing with a gear 9, the latter being mounted upon the governed shaft 2.

The foregoing arrangement is designed to 85 control the rate of rotation of the governed shaft 2 so as to prevent the fire escape from racing. The governor 6 is preferably of the centrifugal type.

Upon governed shaft 2 I mount sprocket 90 wheels 10 and 11 over which sprocket chains 12 and 13 which depend therefrom and are also trained about sprocket wheels 14 and 15, respectively, mounted upon operating shaft 3. At suitably spaced points between 95 the chains 12 and 13 I mount grip rods 16 and tread rods 17. The rods 16 and 17 may be secured in the link pivots of the chains in any desired manner and in the spaced relation indicated. Upon the tread rods 17 I 100 mount tread bars 18, the latter supporting a step or tread 19. The tread bars 18 may be slotted as at 20, to open downwardly, and inside of the bars I secure locking strips 21, as indicated at 22, said locking strips having 105 upwardly opening slots 23, in which the rods 17 seat, thereby locking the bars 18 to said rods. By reason of the fact that the rods 17 are free to turn in their journaled connections in the chain links, the treads are free 110 to be swung, or to adjust themselves, from the inoperative position shown on S lap to

the operative position on the T lap. The free ends of the bars 18 are apertured as indicated at 24 to receive or be connected with the ends of supporting chains 25, the remaining ends of which are connected with the adjacent uppermost grip rod 16. The depth of each tread, or rather the bars 18 thereof is sufficient to permit the pivoted ends of each tread to advance with respect to the chain connected end or portion so that the tread may round the sprocket wheels and be disposed in the hanging inoperative position illustrated at 26, on the S lap. When the fire escape is advanced so that this tread will round wheels 10 and 11, its supporting chain which is in the rear of the tread, with respect to the direction of travel, will first act to hold the tread in an inoperative position, until the tread is advanced somewhat below the upper wheels whereupon the tread will be free to be swung downwardly into a supporting position, as indicated at 27. However, the parts may be fitted in such a manner that the treads will not automatically fall by gravity into a supporting position. When the user desires to mount a tread, he will simply advance the same into a swung out position so that he can step upon the tread and steady himself by grasping one of the grip bars. The weight of the user on the tread on the T side or lap will cause the chains to travel in the direction of the arrow thereby permitting the user to descend under retarding action of the governor 6.

It is an important feature of my invention to provide means for holding the chains taut and I will now describe such means in detail.

40 The lower or operating shaft 3 is mounted in bearings 28 and 29, which bearings are formed integral with bearing arms 30 and 31. Said arms 30 and 31 are pivoted, as at 32, to bearing plates 33 and 34, fixed to the 45 side of the building 1, and as both arms are alike in construction and operation as regards the means for holding the chains taut, only one of said devices will be described in detail.

45 Arm 31 is provided with a pivot lug 35 to which is pivoted at 36, a rod 37, provided with a spring abutment 38. The rod 37 telescopes a sleeve 39 which is pivotally mounted at 40 to a lug 41 on anchorage bar 34. A sleeve 39 is provided with an abutment 42 between which and the abutment 38 is interposed a spring 43. A spring 44 is interposed between abutment 42 and abutment 45 on the end of rod 37. The spring 44 functions 55 to support arm 31 so as to prevent spring 43, which is stronger than spring 44, from forcing arm 31 downwardly too far thus causing undue friction between the chain and sprocket. However, spring 43 holds the 60 chain to a sufficiently taut working condi-

tion and the two springs function to accommodate for contraction and expansion of the chains. It will be understood that the foregoing differential spring device described in connection with arm 31 will be duplicated 70 for arm 30, as shown in Fig. 2.

In cases where it is desired to use the fire escape as a means for elevating firemen or workmen, as the case may be, I provide operating means for actuating the fire escape 75 in a direction reverse from that indicated by the arrow in Fig. 1.

On operating shaft 3, I mount a gear wheel 46 which meshes with a gear pinion 47, on crank shaft 48. Crank shaft 48 is 80 suitably journaled in arm 31 and is provided with a polygonal end 49 for application thereto of an operating crank 50. A ratchet wheel 51 is fixed to crank shaft 48 and contacts with a ratchet pawl 52, mounted at 53, 85 to arrest location of crank shaft 48 in a clockwise direction. Thus when the operating crank 50 is applied to shaft 48 to elevate the treads on the T lap, the crank would be rotated in a contra-clockwise direction. In most instances, the pawl and crank would not be disposed on the fire escape but would be retained by specially designated persons for use in emergency or at other times, so as to prevent the pawl 52 95 from locking the fire escape against use for descent, in case of a fire.

My novel form of chain comprises tooth links 54, for engagement with the teeth 55, of sprocket wheels 15, it being understood 100 that all of the sprocket wheels are of the same construction. The links 54 are connected by wheel engaging links 56, and the latter are drop steel forgings, preferably, so as to afford the maximum tensile strength 105 and durability. Between the teeth 55, the periphery of the wheel 15 is circumferentially grooved, as indicated at 57, there being recesses 58 disposed on opposite sides of the teeth 55 and at the terminals of the grooves, 110 to receive the ends of links 54. Thus without arching the relatively long wheel links 56, I provide means whereby they will negotiate the sprocket wheels and effectively mesh in the grooves thereof without displacing the links 54 off from the teeth 55.

115 It is believed that the novelty and utility of my invention will be fully understood from the foregoing description, and while I have herein shown and described one specific form of my invention, I do not wish to be limited thereto except for such limitations as the claims may import.

I claim:—

120 1. In a fire escape, upper and lower sprocket shaft structures, an endless chain carrier trained about said sprocket structures, fixed bearings for the upper shaft structure, movable bearings for the lower shaft structure, and oppositely acting 125 130

- spring mechanism engaging said movable bearings for supporting the latter against excessive chain tension and urging said bearings toward a working chain tension adjustment, substantially as described. 5
2. In a fire escape, upper and lower sprocket shaft structures, an endless sprocket carrier trained about said structures, relatively heavy and light springs for the lower shaft structure, the former acting to maintain said endless carrier under working tension and the latter acting to prevent excessive tension of said chain carrier, and a governor for limiting the speed of operation 10 of said chain carrier and connected with said upper shaft structure to prevent transmission of load strain on the descending lap of said chain carrier from exerting tension on the ascending lap, substantially as described. 15
3. In a fire escape, upper and lower sprocket shaft structures, an endless sprocket carrier trained about said structures, and spring tension mechanism for one of said shaft structures comprising a relatively heavy spring acting to maintain working tension of said sprocket carrier and a relatively light spring acting to counteract excessive tension, substantially as described. 20
4. In an endless fire escape for buildings, upper bearings fixed to the side of the building, an upper shaft journaled in said bearings and provided with sprocket wheels, a lower shaft, sprocket wheels upon the lower shaft, chains trained about the sprocket 25 wheels of said upper and lower shafts, bearing arms pivoted at their inner ends to said wall and provided with bearings journaling the lower shaft, a rod pivoted to one of said arms and having a spring 30
- abutment, a sleeve pivoted to said wall 40 and telescoping said rod and provided with a spring abutment slidably engaging said rod between the ends of the latter, a relatively strong expansively acting spring on said rod interposed between said 45 rod and sleeve abutments and acting to swing said bearing arms downwardly to maintain said chains taut, said rod having a spring abutment on its free end, and a relatively weak expansively acting spring 50 interposed between said sleeve abutment and the last named rod abutment and acting to support said bearing arms against downward movement sufficient to bind said chains on said sprocket wheels, substantially as described. 55
5. In an endless fire escape for buildings, an upper shaft journaled in bearings fixed to the side of the building, and provided with sprocket wheels, a lower shaft provided 60 with sprocket wheels, bearings pivoted to the side of the building and projecting substantially horizontally outwardly therefrom and having bearings for journaling said lower shaft, and longitudinally extensible 65 mechanism pivoted to one of said arms and to the side of the building and including opposing springs, one acting to tension said chains and the other acting to counteract excessive chain tension, substantially as described. 70

In testimony whereof I affix my signature in the presence of two witnesses.

DANIEL S. BURKHART.
